(57) **CLAIM**

The ornamental design for a trash bag with straps, as shown and described.

DESCRIPTION

FIG. 1 is an isometric view of the trash bag with straps in accordance with the present application.

FIG. 2 is a front view of the trash bag with straps.

FIG. 3 is a back view of the trash bag with straps.

FIG. 4 is a first side view of the trash bag with straps.

FIG. 5 is a second side view of the trash bag with straps.

FIG. 6 is a top view of the trash bag with straps.

FIG. 7 is a bottom view of the trash bag with straps; and, FIG. 8 is an isometric view of the trash bag with straps in use.

The broken line showing of portions of the trash bag with straps is included for the purpose of illustrating environmental structure and forms no part of the claimed design.
